WOMAN'S SANITARY UNDERGARMENT

Joyce L. Jurin, New York, N. Y.

Application August 30, 1947, Serial No. 771,516

6 Claims. (Cl. 128—291)

1

This invention relates to improvements in women's undergarments and more particularly to those in the nature of garter belts or hose supporters provided with means for the support of catamenial devices or sanitary pads, thereby obviating the necessity of special supports or garments.

The object of this invention is to provide a sanitary pad support in combination with a hose support or similar garment, wherein the pad supporting means act in an efficient and positive manner to distribute the strains engendered by use with a maximum of comfort and safety.

A further object of this invention is to provide a garter belt with pad supporting means which will eliminate discomfort to the wearer whether said pad supporting device is in actual use or not.

An additional object of this invention is to provide a pad support in combination with a garter belt, wherein the pad support is instantaneously available for use without any disarrangement of said garter belt, and in which the pad support constitutes an integral part thereof and retains the belt close to the body of the wearer at all times.

Further objects will be described hereinafter in the specifications and will be more particularly pointed out in the appended claims.

Referring to the drawings:

Figure 1 is a perspective view of the garment showing the sanitary napkin in position by broken lines.

Figure 2 is a fragmentary perspective view, partly broken away, showing part of the interior of the garment.

Figure 3 is an elevation showing a tab and clip.

Figure 4 is an elevation showing a tab with clip in position in its retaining pocket.

Figure 5 is a vertical section of a panel and supporting tab.

Figure 6 is a vertical section of a panel and supporting tab showing an end of a sanitary napkin in position.

Fig. 1 illustrates a preferred form of the invention. The garter belt 11 is provided with means to support a catamenial device or sanitary napkin 12. The napkin 12 is shown in broken lines and forms no part of this invention. The garter belt 11 is formed of a front panel 13, a rear panel 14 and two side panels 15 and 16. These panels are secured to each other at their adjacent edges by suitable means so that they form a garment to be supported on the hip or waist portion of the body of the wearer. Along the junction of these panels and running substantially the entire

2

width of said garment 11, transverse stiffening members 17, such as stays or bones, are provided which may be inserted in channels 18 formed by parallel lines of stitching 19 in spaced relation on the overlapping side edges of the panels. At the lower edge of the garment 11, hose supporting bands 20 and clips 21 are provided which are appropriately attached to perform the hose supporting function of the garment 11. These may be of any conventional type.

The napkin 12 is held in place by supporting means which comprise bands of longitudinally extensible elastic material 23, each being provided with a tab 24 and suitable clip 25.

15 The bands of elastic material 23 are provided on the interior side of the front and rear panels 13 and 14. As more clearly shown in Fig. 2, the ends of the elastic bands 23 are secured at 22 to the upper ends of the stiffening members 17 by stitching or in a suitable manner.

20 Each of the elastic bands 23 is in its normal or unextended condition shorter than the fabric of the particular panel 13, 14, with which it is associated so that when the fabric is made taut as 25 when the garment 11 is placed on the body of the wearer the elastic bands 23 are extended and placed under proper tension. It will be readily seen that the tension thus applied will be communicated to the stay members 17 and result in 30 additional support against the body of the wearer thereby preventing any slippage of the garment 11 and increasing its efficiency. It will also be apparent that the elastic bands 23 being under tension will assume positions parallel to the upper edges of the panels 13 and 14, thus preventing the formation of folds or creases which might result in bulges or discomfort to the wearer.

35 The tabs 24, as shown more clearly in Figs. 3 and 4, are identical to each other and are formed of two layers of tape or other suitable non-elastic strip material. The two layers of tape may be separate strips or formed by looping a length of tape over the center portion of each of the elastic bands 23 and secured thereto by stitching or 40 other suitable means. The napkin supporting clips 25 are inserted by means of passing the layer of tape 26 nearest the interior surface of the panels 13 and 14 through the slots 28 provided in the upper portion of the clips 25. The lower portion of tabs 24 comprising both layers of tape are folded upwardly toward the inner surface of the panels 13 and 14. These folds are secured by stitching 29 along the side edges of the lower portion of the tabs. By thus limiting the stitching 29 to the lower portion of the tabs 24, it will 45 50 55

be seen that the clips 25 are free to slide up and down along each of the inner layers of tape, 26, which form a slide therefore and slidably retain each of the clips 25. By limiting the stitching 29 to the side edges of the lower portion of the tabs 24, the upper edges 30 of the folds are left open, thus forming pockets 31 suitable to receive and retain the lower portion of the napkin clips 25 in a fixed position, while the clips 25 are not in use. The clips 25 may be of any conventional type known to the art and may be made of plastic or other suitable rigid material. A preferred type of clip 25 is shown in Fig. 5, wherein the clip 25 is in position within pocket 31. Displacement of the clips 25 from the tabs 24 is prevented, as may readily be seen, and a layer of fabric is at all times provided between the clips 25 and the body of the wearer, thus preventing any skin abrasion or discomfort which might result from contact of the clips 25 with the skin.

When it is desired to make use of napkin supporting means, clips 25 are moved upwardly on the tabs 24 and slide along the tapes 26, and the ends of the napkin 12 are inserted in the napkin retaining portions 32 of the clips 25, as shown in Fig. 6. After the ends of the napkin 12 have been thus inserted in both the front clip 25 and the rear clip 25 of the garment 11, the napkin 12 is adjusted on the body of the wearer. In this condition the downward pull of the napkin exerts additional strain on the horizontal elastic bands 23, which is communicated to the transverse stays 17 along the entire width of the garment 11, increasing the support against the body of the wearer and preventing the entire garment from slipping. Thus the increased downward pull on the garment due to the insertion of the napkin 12 is automatically compensated for by additional support of the stiffening members 17 against the body of the wearer along the entire garment.

While there have been described what are at present considered to be the preferred embodiments of this invention, it will be obvious to those skilled in the art that various changes and modifications may be made therein without departing from the true spirit and scope of the invention.

What is claimed is:

1. A garter belt and sanitary napkin support comprising a front panel, a rear panel and two side panels, secured to each other at their adjacent edges to form a garment, transverse stiffening members positioned at the junction of said panels, a front elastic band and a rear elastic band positioned along the inner surfaces of the front and rear panels respectively and secured at their ends to adjacent stiffening members, napkin supporting means secured to said bands.

2. In a garment of the character described, a plurality of panels secured to each other at their adjacent edges, transverse stiffening members positioned at the junction of said panels, a front elastic band and a rear elastic band positioned along the inner surfaces of the front and rear panels respectively and secured at their ends to adjacent stay members, each of said elastic bands being in its unextended state shorter than the material of the panel between the stay members,

napkin supporting means secured to said bands.

3. In a garment of the character described, a plurality of panels secured to each other at their adjacent edges, transverse stiffening members positioned at the junction of panels, elastic bands positioned along the inner surfaces of the front and rear panels respectively and secured at their ends to adjacent stay members, each of said elastic bands being in its unextended state shorter than the material of the panel between the stay members and provided with tabs secured at the center of each of said bands.

4. In a garment of the character described, a plurality of panels secured to each other at their adjacent edges, transverse stiffening members positioned at the junction of panels, elastic bands positioned along the inner surfaces of front and rear panels respectively and secured at their ends to stay members, each of said elastic bands being in its unextended state shorter than the material of the panel between the stay members to which it is secured, and provided with tabs secured at the center of each of said bands, said tabs comprising a plurality of layers of material having a plurality of folds at their lower ends formed towards the inner surfaces of the respective panels and secured along the side edges of the lower portions of the tabs.

5. In a garment of the character described, transverse stiffening members positioned on the periphery thereof, elastic bands positioned along the inner surfaces of the front and rear portions of said garment and secured at their ends to adjacent stay members, each of said elastic bands being in its unextended state shorter than the material of the garment between the stay members and provided with tabs secured at the center of each of the bands, said tabs comprising a plurality of layers of material having a plurality of folds at their lower ends, formed toward the inner surface of the garment and secured along the side edges of the lower portions of the tabs, supporting clips each slidably mounted on the layer of said tab material adjacent the garment.

6. A garter belt sanitary napkin support comprising a front panel, a rear panel and two side panels secured to each other at their adjacent edges to form a garment, transverse stiffening members positioned at the junction of said panels, a front elastic band and a rear elastic band positioned along the inner surfaces of the front and rear panels respectively and secured at their ends to adjacent stiffening members, each of said elastic bands being in its unextended state shorter than the material of the panel between the stay members to which it is secured and being provided with tabs secured at the center of each of the bands, said tabs comprising a plurality of layers of material having a plurality of folds at their lower ends formed toward the inner surfaces of the respective panels and secured by stitching along the side edges of the lower portions of the tabs forming pockets, supporting clips each slidably mounted on the layer of tab material adjacent the inner surface of the respective panel with which it is associated.

feed screw surrounding the drive shaft and fixed relative to the motor, a tubular plug internally threaded upon the feed screw and externally threaded to engage a threaded socket of an electrode section and means operatively connecting the drive shaft to said plug throughout the entire travel of the plug upon the feed screw.

5. An electrode splicing device for splicing electrode sections having threaded sockets in their ends, said splicing device comprising a reversing motor, a drive shaft upon the motor, a tubular feed screw surrounding the drive shaft and fixed relative to the motor, a tubular plug internally threaded upon the feed screw and externally threaded to engage a threaded socket of an electrode section, said plug having longitudinal grooves therein and driving means upon the drive shaft engaging said longitudinal grooves throughout the entire travel of the plug upon the feed screw.

6. An electrode splicing device for splicing electrode sections having threaded sockets in their ends, said splicing device comprising a reversing motor, a drive shaft upon the motor, a tubular feed screw surrounding the drive shaft and fixed relative to the motor, a tubular plug internally threaded upon the feed screw and externally threaded to engage a threaded socket of an electrode section, said plug having longitudinal grooves therein and a driving spider upon the drive shaft engaging said longitudinal grooves throughout the entire travel of the plug upon the feed screw.

7. An electrode splicing device for splicing electrode sections having threaded sockets in their ends, said splicing device comprising a reversing motor, a draft shaft upon the motor, a tubular feed screw surrounding the drive shaft and fixed relative to the motor, a feed nut threaded upon the feed screw, a tubular plug surrounding the feed screw and fixed to the feed nut, said plug being externally threaded to engage a threaded socket of an electrode section, and means operatively connecting the drive shaft to said plug throughout the entire travel of the feed nut upon the feed screw and rigid radial arms upon said tubular plug.

8. An electrode splicing device for splicing electrode sections having threaded sockets in their ends, said splicing device comprising a base plate, a reversing motor mounted upon the base plate, a drive shaft upon the motor located downward through the base plate, a tubular feed screw surrounding the drive shaft and fixed at its upper end to the base plate, a tubular plug internally threaded upon the feed screw and externally threaded to engage a threaded socket of an electrode section, and means operatively connecting the drive shaft to said plug throughout the entire travel of the plug upon the feed screw.

9. An electrode splicing device for splicing electrode sections having threaded sockets in their ends, said splicing device comprising a base plate, a yoke connected to the base plate for suspending the splicing device above an electrode section,

a reversing motor mounted upon the base plate, a drive shaft upon the motor located downward through the base plate, a tubular feed screw surrounding the drive shaft and fixed at its upper end to the base plate, a tubular plug internally threaded upon the feed screw and externally threaded to engage a threaded socket of an electrode section, and means operatively connecting the drive shaft to said plug throughout the entire travel of the plug upon the feed screw.

10. An electrode splicing device for splicing electrode sections having threaded sockets in their ends, said splicing device comprising a base plate, a reversing motor mounted upon the base plate, a drive shaft upon the motor located downward through the base plate, a tubular feed screw surrounding the drive shaft and fixed at its upper end to the base plate, a feed nut threaded upon the feed screw, a tubular plug surrounding the feed screw and fixed to the feed nut, said plug being externally threaded to engage a threaded socket of an electrode section, said plug having longitudinal grooves therein and a driving spider upon the drive shaft engaging said longitudinal grooves throughout the entire travel of the feed nut upon the feed screw.

11. An electrode splicing device for splicing electrode sections having threaded sockets in their ends, said splicing device comprising a base plate, a reversing motor mounted upon the base plate, a drive shaft upon the motor located downward through the base plate, a tubular feed screw surrounding the drive shaft and fixed at its upper end to the base plate, a feed nut threaded upon the feed screw, a tubular plug surrounding the feed screw and fixed to the feed nut, said plug being externally threaded to engage a threaded socket of an electrode section, said plug having longitudinal grooves therein and a driving spider upon the drive shaft engaging said longitudinal grooves throughout the entire travel of the feed nut upon the feed screw and means for holding said base plate against rotation.
